UNITED STATES PATENT OFFICE

ERNEST R. VIBERG, OF MONTREAL, QUEBEC, CANADA

DRAWBAR-KEY SAFETY DEVICE

Application filed February 7, 1925. Serial No. 7,648.

This invention relates to new and useful improvements in locking devices for draw bar keys and the like, and the object of the invention is to provide a simple device of the 5 class stated which will hold the draw bar key in position at all times and which will be easily unlocked to allow withdrawal of the key for repairs or the like.

Another object is to provide a device of the 10 class stated which will be permanently attached to the car and have no loose parts which may become detached or lost while in operation or during the changing or repairing of the coupler heads or draw bars.

15 Another object is to provide a safe locking device for draw bars, keys, or the like which will not interfere with the horizontal movement of the key in the longitudinal direction of the draw bar.

20 Up to the present time the usual method of locking the coupler to the draw bars has been by means of a key inserted through slots formed in the center sills and engaging with the coupler and draw bar yokes. This key 25 has been provided with a head at one end and drilled at the other end for a cotter pin of the hair pin variety to hold the key in position. This method has proved very unsatisfactory and in many cases the cotter pins 30 have broken through excessive stresses and the keys have worked loose, a state of affairs which has caused costly derailments and, in many cases, possibly loss of life.

To prevent such accidents from occurring, 35 I provide in my invention a casting riveted or otherwise permanently secured to the centre sill of the car. This casting has a locking member slidably and pivotally mounted therein and adapted to hold the key 40 of the draw bar in place without interfering with its movement in the longitudinal direction of the draw bar. The locking member is provided with an inwardly projecting ledge which projects beneath the key to prevent 45 upward movement of the locking member due to vibration or the like. I also provide a slot in the locking member to allow easy access to the key when changing or renewing couplers or draw bar yokes.

50 In the drawings:

Figure 1 is a side elevation of the centre sill of a car with the lock for the draw bar key shown in the locked position.

Figure 2 is a view similar to Figure 1 with the lock shown in the open position. 55

Figure 3 is a sectional elevation taken on the line 3—3 Figure 1.

Figure 4 is a sectional elevation taken on the line 4—4 Figure 1.

Figure 5 is a plan view of the device shown 60 in Figure 1.

Figure 6 is a perspective view of the locking member.

Referring more particularly to the drawings, 65 11 designates the centre sills of a car.

Mounted between the centre sills is the draw bar 12 into the yoke 13 of which is placed the coupler shank 14. Slots 15 and 16 are formed in the yoke and the shank respectively and a key 17 is driven through the 70 slots to hold the coupler to the draw bar. To allow the key to be driven into position slots 18 are formed in the vertical web plates 19 of the sills, said slots being made larger than the keys to allow free movement of 75 same due to the movement of the draw bar. The key is provided with a head 20 at one end to prevent the key from being driven or working itself out of engagement with the yoke and shank. The above description is 80 illustrative of one type of draw bar key construction to which my invention hereinafter described may be attached to hold the key in engagement with the parts which it is desired to hold together. Secured to one of 85

the centre sills by any suitable means, such as the rivets 20^a, is the casting 21 having a central opening 22 to allow easy access to the key for withdrawing same for repairs or the like. Made integral with and projecting outwardly from one end of the casting is the bifurcated bracket 23 through which the pin or rivet 25 passes to support the locking member 24 hereinafter described. 90

The other end 26 of the casting projects outwardly from the base and is slotted to form guides 27 for the end 28 of the locking member. The rib 29^a joining the guides at the bottom forms a support for the end of the locking member when in the locked position. 95 100

tion shown in Figure 1. Ribs 29 and 30 may also be provided in the ends of the casting to position the locking member between them when in the locked position and to hold said locking member against movement until operated manually. In Figure 6 I have shown a perspective view of the locking member 24. The end 32 of the locking member is provided with a slot 33, through which the 10 pin or rivet 25 passes to hold the said member in position in the bifurcated bracket 23. The other end 28 fits into the space between the guides formed in the end 26 of the casting. The centre portion 34 of the locking member projects inwardly and is adapted to engage with the end 35 of the head 20 of the key 17 to prevent same from horizontal movement away from the centre sills. Projecting inwardly from the lower edge 37 of the locking member is the ledge 38 which comes in contact with the lower edge 39 of the head of the key to prevent the locking member from rising upwardly due to vibration or the like. A hole 40 is formed in the 20 centre of the locking member to allow easy access to the key for repairs or the like. The distance between the supports and guides for the locking member is such that the draw bar key may move the maximum allowable 30 amount in the longitudinal direction of the draw bar.

In operation the locking member is lifted to the position shown in Figure 2, that is with the pin 25 engaging with the bottom of the 35 slot. The key is then driven through the slots formed in the draw bar yoke and the coupler with its head projecting outwardly from the centre sill on the side to which the casting 21 is attached. The locking member being pivotally and slidably attached to the bifurcated bracket is first dropped into the horizontal position and then placed between the guides and pushed into the locked position shown in Figure 1, with its lower edge resting on the rib 29. The locking member is then positioned between the ribs 29 and 30. The head of the key is then pressed outwardly so that the inwardly projecting ledge comes in contact with the head 45 to hold the locking member in position should same tend to rise through vibration or the like. In dismantling, a driving tool is inserted through the hole 40 and the key driven inwardly until the head clears the ledge. The locking member is then raised vertically in the guides until the pin engages with the bottom of the slot in said member. The locking member is then raised slightly at one end to allow the key to be easily withdrawn. This device forms a very simple means for holding the draw bar key in position without the necessity of drilling holes in the key in the end remote from its head for cotters or the like. The device is held in the locked 60 position by its own weight and is prevented

from unlocking itself by being slidably mounted in a confined space. It will also be noticed that the lock for the draw bar key is permanently attached to the car and has no loose parts which may become detached or lost while making repairs to the draw bar gear.

Having thus described my invention, what I claim is:

1. Draft key retaining means, comprising a metallic housing adapted to be secured to the side of the center sill so as to protrude laterally therefrom and having a passage transversely therethrough aligned with the draft key slot in the center sill, and means movable across said passage in engagement with the housing.

2. In a device of the character described, the combination with the draft mechanism of a railway car including draft sills having key-receiving openings, of a retainer key associated with various elements of said mechanism and said car and working in said key receiving openings; an enlarged head upon said retainer key preventing removal of the key in one direction, and an abutment element secured to the corresponding draft sill against which said head is adapted to bear; and means for detachably connecting said element to said last named draft sill, said element preventing removal of the key on the other direction.

3. Draft key retaining means comprising a bracket attached to the center sill above and below the draft key slot having two upright portions spaced from the sill and spaced from each other to permit the key to be removed between them, and a key retaining bar inserted behind said upright portions disposed transversely of the head of the draft key and means for removably securing said bar to the upright portions of said bracket.

4. In a railway draft rigging, the combination with the draft sills, of a coupler, a yoke, a key connecting said coupler and yoke and extending through slots in said sills, and a member pivotally connected to said sill and normally disposed in front of said key in key-retaining position said member being movable out of key-retaining position to permit removal of the key.

5. In a device of the character described, the combination with the draft mechanism of a railway car including draft sills having key receiving openings, of a retainer key associated with various elements of said mechanism and said car and working in said key receiving openings; an enlarged head upon said retainer key preventing removal of the key in one direction, and an abutment element secured to the corresponding draft sill against which said head is adapted to bear; said element in normal position preventing removal of the key in the other direction and

being movable out of normal position to permit removal of the key.

6. Draft key retaining means including a bracket for engagement to the center sill and provided with a passage therethrough aligned with the draft key slot in the sill, and means on the bracket for positioning across said passage.

7. In a railway draft rigging, the combination with the draft sills, of a coupler, a yoke, a key connecting said coupler and yoke and extending through slots in said sills, said key having a head at one end, a displaceably mounted key retaining member and means for supporting said member in an operative position close to and opposite the head of the key so as to retain the key in said slots.

In witness whereof, I have hereunto set my hand.

ERNEST R. VIBERG.
